Primary Examiner — Paula Allen Greene*(74) Attorney, Agent, or Firm* — Charles A. Lemaire; Jonathan M. Rixen; Lemaire Patent Law Firm, P.L.L.C.(57) **CLAIM**

The ornamental design for an earpiece as shown and described.

DESCRIPTION

FIG. 1 is a bottom perspective view of an earpiece showing the new design;

FIG. 2 is a left-side view thereof;

FIG. 3 is a right-side view thereof;

FIG. 4 is a front view thereof;

FIG. 5 is a back view thereof;

FIG. 6 is a top view thereof; and,

FIG. 7 is a bottom view thereof.

The broken lines depict portions of the earpiece that form no part of the claimed design.
